JOHANN JACOB ZUBLER, OF BROMBACH, GERMANY, ASSIGNOR TO MASCHINENFABRIK
RÜTI FORMERLY CASPAR HONEGGER, OF RÜTI, SWITZERLAND.

AUTOMATIC STOPPING DEVICE FOR POWER-LOOMS WITH FIXED REEDS.

1,104,951.

Specification of Letters Patent.

Patented July 28, 1914.

Application filed May 16, 1913. Serial No. 768,082.

To all whom it may concern:

Be it known that I, JOHANN JACOB ZUBLER, a citizen of the Republic of Switzerland, residing at Brombach, Grand Duchy 5 of Baden, Germany, have invented certain new and useful Improvements in Automatic Stopping Devices for Power-Looms with Fixed Reeds; and I do hereby declare the following to be a full, clear, and exact 10 description of the invention, such as will enable others skilled in the art to which it appertains to make and use the same, reference being had to the accompanying drawings, and to letters of reference marked 15 thereon, which form a part of this specification.

In previous constructions of power looms with a fixed reed in which the automatic tripping devices were actuated by the shuttle or shuttle feelers, the lay swords and the frame of the loom were subjected to severe shocks and consequently these parts had to be made of ample dimensions while the increased weight of the movable parts 25 thus entailed was detrimental to the operation of the loom at high speed so that such looms could be operated only at a low speed. In looms in which the tripping devices are actuated by a loose reed the lay and the 30 frame of the loom may be made lighter. These looms have, however, the disadvantage that in consequence of the reed being easily movable they are not suitable for the production of heavy textures, so that for 35 such heavy textures only looms having a fixed reed can be employed.

The subject of the present invention is an automatically operating tripping device for power looms having a fixed reed in which 40 the lay swords are wholly relieved from the shock occurring on stoppage of the loom, while the frame of the loom is relieved from such shock to a very large extent, and consequently these parts may be made of lighter 45 proportions, the lighter construction permitting of operation of the loom at higher speed. In this manner danger of breakage of the batten supports and parts of the frame by hard impacts is obviated. In the 50 present construction of the tripping devices

the impact of the shuttle is slight, as the braking effect exercised by the shuttle box tongues upon the shuttle is not greater than in looms with a free reed and consequently the wear of the entire mechanism is minimized.

In the accompanying drawings Figures 1 and 2 are side elevations illustrating the invention in two forms.

The same reference letters denote similar parts in the several views.

Referring first to Fig. 1, 1 denotes the usual crank shaft of the loom upon which is mounted in known manner the fly-wheel 2 serving as a brake disk; also fixed upon the crank shaft is a disk 3 on the periphery of which disk is formed a tooth 4. On a stationary stud 7 on the frame 5 is pivotally mounted a lever 6, upon the forward end of which is pivotally mounted on a pin 8 a pawl 9 designed to engage the tooth 4, and provided with a lateral arm 10 which carries a roller 11. A spring 12 one end of which is connected to the lever 6 and the other end of which is connected to the pawl 75 9, tends to draw the pawl continuously against the periphery of the disk 3. 13 is a buffer spring for the roller 11. The forward end of the lever 6 is suspended from a bracket 16 of the frame by means of a rod 14 surrounded by a helical spring 15. The forward end of the lever 6 is rounded and is adapted to engage a lever 18 pivoted upon the stationary stud 17, said lever 18 acting through the intermediary of a rod 19 upon the usual stop motion lever to stop the operation of the loom. 20 denotes one of the swords supporting the lay 21 with the fixed reed 22. 24 is one of the shuttle feeler levers, 23 the shuttle box tongue and 25 the shaft carrying the shuttle feeler levers. Upon the latter is secured an arm 26 the free end of which is adapted to engage the roller 11. A spring 27 is designed to draw the arm 26 upwardly into such position that its rearward end moves past the roller 11. When the shuttle 28 enters the shuttle box correctly the levers 24 are pressed backwardly in the usual manner and the arm 26 pressed on the return movement of the lay, 100

upon the roller 11 whereby the pawl 9 is tilted in such manner as to prevent it from entering into engagement with the tooth 4 of the continuously rotating disk 3. When 5 however, the shuttle does not enter the box correctly the spring 27 maintains the arm 26 in its raised position so that upon the return movement of the lay, the arm passes over the roller 11, without engaging it and 10 consequently the pawl 9 remains in contact with the periphery of the disk 3 so that the tooth 4 is engaged by the pawl 9 the crank shaft 1 is thus stopped and the lever 6 depressed by the pawl 9 the forward end of 15 said lever 6 engaging the lever 18 and shifting it in such manner that the stop motion lever (not shown) is brought into action through the intermediary of the rod 19 to stop the operation of the loom. The impact 20 of the tooth 4 transmitted by the pawl 9 upon the lever 6 is cushioned by the spring 15. The lay is wholly relieved from such impact, the greater part of which is absorbed by the crank shaft 1, while only a 25 small portion thereof is transmitted through the spring 15, to the framing so that breakage of the latter is practically impossible. The batten and the framing may consequently be made of lighter proportions than 30 was heretofore possible. A further advantage of this construction is that the operator when unweaving and looking for the weft at a time when the shuttle is not in the shuttle box is enabled to move the parts of 35 the loom in reverse direction without being compelled to press the shuttle feeler levers 24 backwardly by hand inasmuch as the tooth 4 of the disk 3 will move beneath the pawl 9. When the forward end of the lever 6 is depressed a brake shoe 31 carried by 40 the rear end 29 of said lever by means of an adjustable screw-bolt 30 is brought into engagement with the periphery of the disk 2 and effects the final braking of the loom.

45 In the modified construction shown in Fig. 2 the pawl 9 remains normally at rest and is only brought into engagement with the tooth 4 of the disk 3 when the shuttle having failed to enter the shuttle box the tongue 50 23 has not been pressed backwardly. For this purpose a lever 33 and a disk 34 having a tooth 35 are mounted upon a shaft 32 disposed parallel to the shaft 25. The arm 33 is connected with a downwardly extending 55 arm 38 of the pawl 9 by means of a connecting rod composed of two telescoping parts 36 and 37 having a pin-and-slot connection 39, 40, and a spring 41 tending to draw the parts toward one another. During the normal 60 operation of the loom, a spring 42 tends to move the disk 34 in such manner that the pawl 9 will remain out of engagement with the disk 3. However, if the shuttle fail to enter the shuttle box, an arm 43 on the shaft

25 carrying the shuttle feeler levers 65 engages the tooth 35 of the disk 34 so that the two-part rod 36-37 turns the pawl 9 toward the disk 3, the spring 41 holding the pawl 9 resiliently in contact with the periphery of said disk 3 so that the tooth 4 engages the pawl 9 thus stopping the crank shaft. It will be understood that in lieu of being mounted on a rotatable part the pawl 9 might be mounted upon a rectilinearly movable part. 70 75

What I claim is:—

1. In combination, with the frame, the moving lay, the shuttle, the rotary driving member journaled in the frame, including a fly wheel, and provided with a peripheral tooth, and the stopping mechanism to be actuated, of a cushioned lever fulcrumed in the frame and adapted to actuate the stopping mechanism, a pawl carried by and movable upon the lever into and out of the path 80 of the tooth of said member, a brake on said lever engageable with said fly wheel, and means, actuated by the shuttle, for moving the pawl, substantially as described. 85

2. In combination, with the frame, the moving lay, the shuttle, the rotary driving member journaled in the frame, including a fly wheel, and provided with a peripheral tooth, and the stopping mechanism to be actuated, of a cushioned lever fulcrumed in 90 the frame and adapted to actuate the stopping mechanism, a pawl pivoted on said lever, a spring normally holding the pawl in the path of the tooth, a brake on said lever engageable with said fly wheel, and means, actuated by the shuttle, for moving the pawl out of the path of the tooth, substantially as described. 95 100

3. In combination, with the frame, the moving lay, the shuttle, the rotary driving member journaled in the frame, including a fly wheel, and provided with a peripheral tooth, and the stopping mechanism to be actuated, of a lever fulcrumed in the frame 105 and adapted to actuate the stopping mechanism, a rod connected to the lever, a spring cushioning said rod on the frame, a pawl carried by and movable upon the lever into and out of the path of the tooth of said member, a brake on said lever engageable 110 with said fly wheel, and means, actuated by the shuttle, for moving the pawl, substantially as described. 115

4. In combination, with the frame, the moving lay, the shuttle, the rotary driving member journaled in the frame, including a fly wheel, and provided with a peripheral tooth, and the stopping mechanism to be actuated, of a lever arranged substantially 120 horizontally and fulcrumed in the frame and adapted to actuate the stopping mechanism, a brake carried by said lever rearward of 125 its fulcrum and adapted to peripherally en-

gage said fly wheel, a pawl pivoted on the lever forward of its fulcrum and movable thereon into and out of the path of said tooth, a spring normally holding the pawl in said path, and means, actuated by the shuttle, for moving the pawl out of said path, substantially as described.

In testimony whereof, I have signed my name to this specification in the presence of two subscribing witnesses.

JOHANN JACOB ZUBLER.
